UNITED STATES PATENT OFFICE.

EDWARD WARREN BODMER, OF HARRISBURG, PENNSYLVANIA.

DESIGN FOR AN INDICATOR.

SPECIFICATION forming part of Design No. 30,019, dated January 17, 1899.

Application filed December 17, 1898. Serial No. 699,608. Term of patent 7 years.

To all whom it may concern:

Be it known that I, EDWARD WARREN BODMER, a citizen of the United States, residing at Harrisburg, in the county of Dauphin, State of Pennsylvania, have invented a certain new and original Design for Indicators, of which the following is a description, reference being had to the accompanying drawings and to the letters and figures of reference marked *to* thereon.

My invention relates to a new and original design for indicators; and it consists in an indicator of the configuration and ornamentation hereinafter described.

15 The design is illustrated in the accompanying drawings, in which—

Figure 1 is a plan view, and Fig. 2 is a cross-section on line *xx* of Fig. 1.

Said indicator comprises a flat plate A, provided with the lines B, C, D, E, and F, representing a portion of a frame of a bicycle.

G and H represent indicator face-plates, each provided with the central opening 1 and with the radial cross-lines 2 and 3, extending

from the center to the circumference I of the 25 face-plate, said circumference being represented as a raised beading. The face-plate G is provided with the two lines 4 and 5, extending from the center to the circumference, while the face-plate H is provided with the 30 radial line 6, said lines 4, 5, and 6 forming, with the lines B and F, a representation of the rear and front forks of a bicycle. The raised circumference I of the indicator face-plates extends to a point below the plane of 35 the flat plate A.

Having thus described my invention, what I claim, and desire to secure by Letters Patent, is—

The design for an indicator, substantially 40 as shown and described.

In testimony whereof I affix my signature in presence of two witnesses.

EDWARD WARREN BODMER.
